UNITED STATES PATENT OFFICE.

JAMES JOSEPH WOLFF, OF NEW YORK, N. Y.

TAG-HOLDER.

1,368,084.

Specification of Letters Patent.

Patented Feb. 8, 1921.

Application filed August 21, 1919. Serial No. 318,944.

To all whom it may concern:

Be it known that I, JAMES J. WOLFF, a citizen of the United States, and a resident of the city of New York, borough of the Bronx, in the county of Bronx and State of New York, have invented new and useful Tag-Holders, of which the following is a full, clear, and exact description.

This invention relates to holding devices for tags, identification cards and the like, and has for an object to provide an improved construction wherein means are presented for thoroughly protecting the tag against injury or loss.

Another object in view is to provide an improved holder wherein the construction will permit the ready insertion or removal of the tag, but will prevent the accidental loss thereof.

A further object of the invention is to provide an improved construction which may be placed on almost any part of a trunk or other article and at the same time be out of the way.

In the accompanying drawing:

Figure 1 is a perspective view of one end of a trunk with an embodiment of the invention applied thereto.

Fig. 2 is a plan view on an enlarged scale of the holder shown in Fig. 1, certain parts being broken away for better disclosing the invention.

Fig. 3 is an enlarged sectional view through Fig. 2 on line 3—3.

Fig. 4 is an enlarged fragmentary sectional view through Fig. 2 on line 4—4.

Referring to the drawing by numerals 1 indicates a trunk to which the holder 2 is secured by any suitable means, as for instance rivets 3. The holder 2 is formed with a back preferably of solid sheet metal provided with a frame or spacing member 5 riveted or otherwise rigidly secured thereto. The same rivets which hold frame 5 in place also hold the front plate 6 in place, said front plate being formed with a thumb opening 7 through which part of the tag 8 may be seen and may be grasped for removal if desired. In order to hold the tag 8 in place normally sliding locking members or stops 10 and 11 are provided. Each of these locking members is formed with a thumb engaging head 11, a post 12 and a guiding foot 13 slidably positioned in the respective grooves 14 (Fig. 3). These

grooves are in line with and also parallel with the slots 15 and 16 through which the posts 12 of the locking members 10 and 11 extend.

When it is desired to use the tag holder 60 the locking members 10 and 11 are separated as far as possible and then the card or tag 8 inserted after which the members 10 and 11 are brought as close together as possible. This will lock the tag against accidental removal. The tag 8 may have any desired information thereon and does not interfere with the usual tags now in common use by express companies and the like. It will be noted that the tag 8 is thoroughly 70 protected against injury or accidental loss. The friction of the foot 13 and other parts of the locking member against the surrounding parts of the holder retains the members firmly in their locked or unlocked 75 positions.

What I claim is:

1. A tag holder comprising front and back plates spaced apart, a frame connecting said plates together except at one edge, 80 said front plate having a slot adjacent each end, and sliding locking members extending through said slots for locking a tag in the holder.

2. A tag holder comprising a pair of 85 spaced plates, a frame connecting said plates, one of said plates having a slot adjacent each end while the other plate is formed with a groove at each end facing said slots, and a reciprocating locking member for 90 each slot, each of said locking members being formed with a thumb engaging head, a post extending through the slot, and a foot slidably positioned in the groove.

3. A tag holder comprising a pair of 95 spaced plates, a frame connecting said plates, one of said plates having a slot adjacent each end while the other is formed with a groove facing said slots, and a reciprocating locking member for each slot, 100 each of said locking members being formed with a post extending through said slot and an elongated foot extending transversely of the post and frictionally engaging one of said plates in said groove, said foot being 105 of sufficient length to produce ample friction for holding the post in any of the adjusted positions.

JAMES JOSEPH WOLFF.
